UNITED STATES PATENT OFFICE

2,514,001

CABINET CONSTRUCTION FOR SINKS

Harvey G. Knuth, Elgin, Ill., assignor to Lyon Metal Products, Incorporated, Aurora, Ill., a corporation of Illinois

Application February 23, 1945, Serial No. 579,458

5 Claims. (Cl. 312—169)

1

This invention relates to, preferably, a kitchen cabinet construction, and more particularly to a cabinet construction for enclosing a sink.

Among the objects of the present invention are to provide a cabinet construction of sheet material for enclosing a sink and particularly for enclosing the space beneath the sink to provide a storage compartment or chamber therefor and for providing the front of said compartment with doors to close or give access to said compartment, the doors being disposed substantially flush with the remaining portions of the front wall of said cabinet construction and wherein the upper portion of the stationary front wall of the cabinet construction above the doors is especially constructed to provide not only an upper ventilation opening for the space or chamber underlying the same, but also to provide an outwardly extending overhanging ledge or lip which will overlie the upper edge portions of the door or doors closing the front of the compartment underlying the sink so that water spattered or dripping over the front edge of the sink and running down the front wall of the sink will be deflected away from the top edge of the doors whereby they will remain dry, clean, and will preserve their original appearance, and whereby also in cleaning the front of the cabinet this overhanging lip will tend to deflect a cleaning cloth or a wet rag from the upper edge of the doors whereby to avoid catching the cloth in the upper edge of the doors and to avoid moistening the upper edge of the doors which, when the moisture has dried, will leave the upper edges unsightly and dirty, and whereby also a very ornamental finish is given to the juncture line between the upper edge of the doors and the lower edge of the front wall of the cabinet above the door; to provide these and other objects of invention as will be apparent from a perusal of the following specification when taken in connection with the accompanying drawing, wherein:

Figure 1 is a perspective view of a sink enclosed in a sheet material cabinet construction, preferably a sheet metal cabinet construction;

Figure 2 is a section taken on the line 2—2 of Figure 1; and

Figure 3 is a fragmentary perspective view 50 of a sink. The upper part of the

2

with the lower portion of one door open, showing the lower ventilation openings.

Referring now to the drawings in detail, the invention includes an enclosing cabinet construction for the usual sink 2 which may be of any desired construction including the drain 4, the water inlet 6, and the control faucets 8 and 10. The top 12 of the sink overlies at 14 the upper horizontal flange 16 of the bowl 2. At 15 the front the top is provided with a sheet metal vertical wall 18 which overlies and forms a liquid-tight seal as at 20 with the linoleum top 12 of the sink. The latter, as shown at 14, overlies the flange 16 of the bowl. The front wall 18 is preferably provided with an inwardly turned flange 19. The front vertical wall 24 forming the upper portion of the enclosing cabinet construction is preferably provided with an inturned flange 22 fixed to the front beam or 20 support member 21 of the cabinet. The compartment 26 beneath the sink is generally used for the storage of dustpans, cleaning rags, soap, basins and other commodities. The cabinet includes a basal vertical wall 28 having an inwardly extending basal flange 30 and an upper flange 32 for receiving the floor panel comprising the spaced horizontal walls 34 and 36 which are closed at their front by means of the wall 38. It will thus be seen that the front part of the 30 cabinet overlies and overhangs the front wall at the base of the cabinet. In the construction shown, the lower wall 34 is provided at its front with an integral right angle bend to provide wall 38 which in turn is provided with an upper horizontal flange 40 which is welded at 42 to the upper edge of the horizontal wall 36. The closure portion 44 shown to the left of the door 46 may be either another hinged door or may be the front of a drawer that pulls out. Closure 40 means for the compartment 26 is illustrated as including two doors 46 and 48 which are hingedly connected to the vertical stationary posts 50 and 52 forming a stationary part of standard cabinet construction. The front portions of the floor member 34 and 36 which overhang the vertical basal wall 28 are provided with ventilating openings 54 and 56 for the purpose of permitting air to flow into the cabinet as is required by various city ordinances when the cabinet is associated with a sink. The upper part of the

opening below the wall 24 is reinforced and rigidified by a horizontally extending top stationary channel bar 58.

The important feature of the present invention resides in providing the lowermost edge of the vertical sheet metal wall 24, substantially co-extensive with the width of the sink, with an outwardly depending, preferably curved lip or louver 60, the lower edge 62 of which is spaced from the upper edges 64 of the doors 46 and 48 and extends outwardly of and above the front surface 66 of these doors and preferably beyond the outermost vertical plane of the handle 68 so that any dripping of moisture, condensation, or what not, will drop past the handle 68 and the front surface 66 of the closure means, onto the floor. Particular attention is called to the fact that by means of this louver any water slopping over the front of the sink and running down the front vertical wall 24 will descend by gravity over the outwardly curved wall 60 of the louver and will drop onto the floor but will not dampen the upper edges of the doors 46 and 48. Thus the upper edges of these doors when closed will not be subject to accumulation of moisture or dirt or dust, particularly moisture, and therefore will not deteriorate and will not present an unsightly appearance when opened.

In addition, there will be no need of constantly wiping off the front vertical wall 24 of the sink as heretofore, and furthermore because of the presence of the louver and the absence of any open louvers in the open wall 24 of the sink, no moisture can escape into the closed compartment beneath the sink. In addition, if a cleaning rag is brushed across the surface 24 it will not tend to catch on the doors because the louver 60 will deflect it away from the door. Also, by forming the louvers 60 substantially co-extensive in length with the width of the sink basin or bowl 2 the adjoining vertical surfaces 70 and 72 of the front wall of the entire cabinet are protected from moisture. It will be noticed that by forming the louver in the manner indicated, an opening is provided between it and the top edges of the door which provides an upper ventilation opening for the cabinet so that a complete circulation is possible through the cabinet through the lower ventilation openings 54 and 56 and the louver 60. In addition to this, the louver 60 in the manner shown forms a very ornamental surface for the otherwise unsightly upper edges of the hinged doors 46 and 48. When the doors are closed the ventilation openings 56 are of course not seen.

Obviously the invention is not limited to the specific details of construction disclosed herein but is capable of other modifications and changes without departing from the spirit and scope of the appended claims.

Having thus described the invention, what I claim as new and desire to secure by Letters Patent is:

1. A kitchen cabinet having walls enclosing a sink and including a stationary front upper vertical wall, said cabinet walls forming a compartment beneath the sink, closure means for the front of the compartment normally disposed in a closed position below said stationary front upper vertical wall, vertical hinge means for said closure means to permit the closure means to swing to open and closed position, said closure means for the front of the cabinet when in closed position lying substantially in the plane of said vertical upper front wall, and said upper front

vertical wall for substantially its entire extent above said closure means when the latter is in closed position having an outwardly extending wall portion projecting outwardly beyond the vertical plane of said front wall of the cabinet and spaced forwardly of and immediately above the upper edges of the closure means whereby to deflect water away from the upper edges of said closure means while permitting opening and closing of the closure means.

2. The combination of a kitchen sink, a front cabinet construction therefor providing a closure for the space beneath the sink, said cabinet construction including a front stationary vertical wall and closure means for closing an opening immediately below said stationary vertical wall, vertical hinge means for said closure means for permitting said closure means to swing to open and closed position below said front vertical wall and for giving access to the space beneath said sink, substantially the entire lower edge of said front vertical wall immediately above the upper edge of the closure means when in closed position having an outwardly extending stationary lip for deflecting water running down the front wall of the cabinet away from the upper edge of said closure means and for hiding the upper edge of the closure means above a horizontal viewing position when in closed position.

3. In combination with a sink, a stationary front vertical wall construction for a cabinet enclosing the sink, said front wall depending below the top of the cabinet a relatively short distance and providing a free horizontal edge forming an opening in the front of the cabinet below said edge, vertically hinged closure means for the opening disposed below said lower edge of said front wall and forming when closed a vertical extension of said front wall, substantially the entire lower edge of said front wall above said closure means being formed outwardly to provide an upper ventilating louver for said space beneath said sink and for deflecting moisture, dirt and liquid away from the upper edge of said closure means, the lower edge of said outwardly extending portion being spaced from the upper edge of the closure means to permit opening and closing thereof and providing an air circulating passage to the interior of the passage when the closure means is closed.

4. In a cabinet construction for enclosing a kitchen sink, said construction including a horizontal top wall overlying the upper wall portion of said sink, and a front substantially vertical stationary wall, swingable front closure means having vertically extending hinge means, said closure means when swung to closed position lying substantially flush with the plane of the front vertical wall and substantially the entire lower edge of said front vertical wall being formed outwardly in spaced relation from the upper front edge of said closure means when closed, the outer lower edge of said front vertical wall lying slightly above and spaced from the upper edge of said closure means to permit opening and closing thereof and forming an air circulating opening for said cabinet above the closure means when closed.

5. In combination with a sink, a cabinet construction for enclosing the sink comprising a basal support, a floor member overlying said support, said floor member forming a base of a compartment and projecting at the front beyond said basal support, a top having an opening in registration with the bowl of said sink for clos-

ing the top of the cabinet, a vertical front stationary wall for said cabinet closing the upper portion of the compartment below said sink, said cabinet walls below said stationary front wall having an opening, closure means disposed below said stationary front vertical wall when in closed position, vertical hinged means for said closure means, the outer face of said closure means when in closed position lying substantially flush with the plane of the upper front stationary wall of said cabinet, aperture means in the forwardly projecting portion of said cabinet floor, said upper front stationary wall of the cabinet being imperforate and having its entire lower edge extending outwardly to overhang the upper edge of said closure means when the latter is in closed position, said lower edge of said overhanging front stationary wall being spaced from the upper edges of said closure means when closed to deflect dirt, moisture and other matter away from the upper edges of said closure

5 means when closed, said outwardly bent lower edge of said front wall of said cabinet constituting an upper ventilating louver and substantially hiding said upper edge of said closure means above a horizontal viewing position when in closed position.
